UNITED STATES PATENT OFFICE.

OSCAR F. MALMBERG, OF CHICAGO, ILLINOIS.

CONVERTIBLE BENCH.

1,139,693.

Specification of Letters Patent. Patented May 18, 1915.

Application filed April 24, 1913. Serial No. 763,273.

To all whom it may concern:

Be it known that I, OSCAR F. MALMBERG, a citizen of the United States, and a resident of the city of Chicago, county of Cook, 5 and State of Illinois, have invented certain new and useful Improvements in Convertible Benches, of which the following is a specification.

My invention relates to convertible 10 benches and more particularly to benches adapted to be converted into beds or couches.

The object of this improvement is to provide a bench having foldable side rails and 15 which is adapted to be extended and formed into a bed or couch.

Other objects will appear hereinafter.

The invention consists in the combinations and arrangements of parts hereinafter 20 described and claimed.

The invention will be best understood by reference to the accompanying drawings forming a part of this specification, and in which,

25 Figure 1 is a plan view of a bench embodying my invention and having its seat, or lid opened up to expose the folded portions, Fig. 2 is an enlarged central section of the same showing the lid or seat portion closed, Fig. 3 is an enlarged fragmental view of one corner portion of the same, Fig. 4 is a plan view of the device in extended condition, Fig. 5 is a central section of the same, and Fig. 6 is an enlarged fragmental 30 section of a corner portion of the device.

35 The frame of the device comprises a pair of end members and a pair of foldable sides connecting the same and the whole supported upon corner posts or legs.

40 Referring to the drawings 8—8 indicate the transverse end members of the frame to each of which is rigidly secured a pair of legs 7. Each end member 8 together with the respective legs 7 thus forms a rigid end 45 member. Rigidly secured to each end member is a section 9 of the respective side rails.

These sections are preferably of the same depth as the end members 8 and project from opposite sides of the respective end 50 members so that when brought together the free ends of the sections 9 abut the opposite end members at the opposite ends from that to which the corresponding section is fixed thereby forming a rectangular frame with 55 the upper edges of the members 8 and 9 in the same plane, and with the lower edges of

the same preferably in a common plane. Pivotedly secured to the under edges of the members 8, preferably adjacent the ends thereof, are bars 20 terminating in hooks 60 adapted to engage pins on the under edges of the opposite members 8 to lock the frame in closed position.

Hingedly connected to one of the members 8 as by hinges 32 is a seat portion 31 65 which rests upon the upper edges of the members 8 and 9 when the device is in position to be used as a bench. A stop member 33 preferably comprising a pair of hingedly connected links constitutes means to limit 70 the outward swing of the member 31. The portion 31 when swung outwardly constitutes a pillow rest when the device is used as a couch.

The free ends of the sections 9 are rabbed as at 9' forming tongues or stops 9'', the purpose of which will appear hereinafter. Hingedly connected to the rabbed portions of the sections 9 are a pair of hingedly connected side rail sections 80 10—10, the opposite ends of which are hingedly connected to the opposite end members 8. The hinges 11 which connect the sections 10 to the sections 9, the members 8 and to each other are so arranged as 85 to allow said sections to fold inwardly when the device is collapsed; and the stops 9'' constitute means for limiting the outward swing of the sections 10 and maintain them in alinement when the device is extended for 90 use as a couch. Catches 12 are pivotally connected as at 13 to one of the sections 10 of each rail to span the abutting ends of the said section to lock the same in alinement. The sections 10 are of less depth 95 than that of the sections 9 and have their upper edges arranged in a plane below the upper edges of the sections 9, and their lower edges in a plane above that of the lower edges of the sections 9 for reasons 100 which will appear hereinafter.

Pivotally secured to the under edge of one of the sections 10 upon each side of the device are bars 15 which are swung inwardly when the device is extended and the free 105 ends of said bars are provided with interlocking portions to hold the same in alinement and to relieve the strain in the catches 12 to prevent collapsing of the side rails when the device is in use as a couch. Preferably the ends of one of said bars is provided with a threaded stud or pin and the

other bar with a notch to receive the pin, and a thumb nut is arranged upon the threaded pin to clamp upon the bifurcated or notched end of the opposite bar.

5 Pivots secured to the upper edge of one of the sections 10 of each side rail is a hook or catch 18 adapted to engage pins 19 on the adjacent section 10 when the device is in folded or collapsed condition. The catches 18 are arranged adjacent the ends that are 10 hingedly connected to the sections 9 and members 8 and thereby constitute additional means for holding the frame in rigid position when folded for use as a bench. The catches 18 and bars 20 thereby constitute 15 means for rigidly securing the device in folded position to prevent spreading of the legs. By having the upper and lower edges of the members 10 in the relative positions 20 above described relative to the corresponding edges of the sections 9 the catches 18 and bars 15 are invisible when the device is folded and will not interfere with the proper operation of the portion 31. It 25 should be noted that the sections 10 are substantially co-extensive in length so that when the device is folded they lie parallel to each other and to the end members 8; and also that the length of the stops 9' is greater 30 than the combined thicknesses of the sections 10 when folded so that said sections will not interfere with the ends of said stops, which constitute the ends of the sections 9, from snugly engaging the end members.

35 The flexible material 21 preferably a suitable fabric is secured to one of the end rails 8 by means of a bar 22 at one of its ends. The other of its ends is looped and a bar 23 secured therein. The ends of the bar 23 are provided with arms 24 pivoted as 40 at 25 in a manner so that said arms 24 may be moved from the full line to the dotted line position indicated in Fig. 3. The arms 45 24 are positioned in the full line positions when used to support the fabric 21 and in the dotted line position when the fabric is wound around the bar 23 when the device is in its folded condition. The free ends 50 of the arms 24 are provided with pins 26 which are adapted to engage within sockets 27. Stops 28 are provided on the side rails in positions to support the ends of bar 23 when the device is opened out to bed form, 55 as will be readily understood from Figs. 4, 5 and 6.

60 Ears 29 are secured to the fabric 21 along its edges and buttons 30 are provided along the sides of the side rails 9 to engage the ears 29 to stretch the fabric taut transversely and to prevent the sagging of said fabric when a heavy person or other weight is supported thereby.

65 In operation, the device is folded by swinging the members 10 on the hinges 11

to substantially the positions indicated in Fig. 1. The catches 18 are locked on their cooperating pins 19 to lock the top portions of the sides and locking bars 20 are locked to lock the bottom portions of the sides to 70 facilitate rigidity of the construction when the device is folded in condition for use as a bench. When the device is extended for use as a bed the fabric 21 is unrolled and the pins 26 of arms 24 are engaged in the 75 sockets 27 and the bar 23 is pressed downwardly until it rests on the stops 28, the latter being below a plane extended from the top of bar 22 and through bar 23, to stretch fabric 21 longitudinally of the device. The ears 29 are engaged on the buttons 30 to hold the fabric taut laterally. The spacing bars 15 are locked in the 80 positions indicated in Fig. 4 to further facilitate rigidity of the construction when the 85 device is used as a bed.

90 While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of 95 the appended claims.

Having described my invention what I claim as new and desire to secure by Letters Patent is:

1. In a device of the kind described, the 100 combination of a frame having rigid end portions and foldable side rails, each side rail comprising three pivotally connected sections, one section of each rail being rigidly connected to the adjacent end portion; a catch at the pivotal point between two 105 of the sections in each side portion locking such members in alining relation; and an extension on one member in each side portion extending beyond the pivotal point 110 of such member and its next adjacent member and engaging one side of the latter, substantially as described.

2. In a device of the class described, a 115 pair of transverse end members each provided with a pair of legs, a side rail section rigidly connected to each of said end members and upon opposite sides of the device, a pair of hingedly connected side rail sections hingedly connected at one end to the 120 respective first mentioned sections and at the other end to the opposite end members, the hinges being arranged to permit said sections to fold inwardly, catches adapted to rigidly connect the upper edges of the last mentioned sections at points adjacent the ends connected to said first mentioned sections and points adjacent said end members respectively and pivotally mounted bars on 125 the lower edges of the end members adapted 130

to connect the same when the device is in folded position, substantially as described.

3. In a device of the class described, a pair of transverse end members each provided with a pair of legs, a side rail section rigidly connected to each of said end members and upon opposite sides of the device, with its upper and lower edges in the same plane with the upper and lower edges 10 of said end members respectively, a pair of hingedly connected side rail sections hingedly connected at one end to the respective first mentioned sections and at the other end to the opposite end members, with 15 their upper edges in a plane below that of the upper edges of the first mentioned sections and their lower edges in a plane above the lower edges of said first mentioned sections, the hinges being arranged to permit

said sections to fold inwardly, catches 20 adapted to rigidly connect the upper edges of the last mentioned sections and points adjacent the ends connected to said first mentioned sections and points adjacent said end members respectively, pivotally mounted 25 bars on the lower edges of the end members adapted to connect the same when the device is in folded position, and a seat portion hingedly connected to one of said end members, substantially as described. 30

In testimony whereof I have signed my name to this specification in the presence of two subscribing witnesses.

OSCAR F. MALMBERG.
